Frederick Curtis

United States Patent Office.

ERASTUS C. PHILBRICK, OF BATH, MAINE.

Letters Patent No. 96,953, dated November 16, 1869.

IMPROVEMENT IN LIP-SHIELDS.

The Schedule referred to in these Letters Patent and making part of the same.

To all to whom these presents shall come:

Be it known that I, ERASTUS C. PHILBRICK, of Bath, in the county of Sagadahoc, and State of Maine, have made an invention of a new and useful device for barbers' use, which I term a "Lip-Protector;" and do hereby declare the following to be a full, clear, and exact description thereof, due reference being had to the accompanying drawings, making part of this specification, and in which—

Figure 1 is a perspective view, and

Figure 2, a longitudinal section of my invention.

The annoyance and inconvenience, not to say uncleanliness, of the present mode of dyeing a person's moustache and beard are now so generally felt, that any device which shall afford protection against such results, will be appreciated and used.

As the dyes now used are applied to the beard or moustache without any means of insuring the skin against being acted upon by them, the skin, as a consequence, becomes more or less discolored.

To erase this disfigurement, liquids are employed which are injurious to the cuticle in many respects, and which often, if not invariably, cause sore lips in the effort to remove discoloration, caused by the dye which comes in contact with them, and which heretofore could not be avoided.

The object of this invention is to obviate these objections, by entirely preventing the dye from coming in contact with the skin; and consists in the employment of a plate, of any suitable material, of a semi-cylindrical shape, which is inserted between the hair and skin, and so as to present a perfect barrier to the contact of the dye with the skin below it.

The drawings accompanying this specification illustrate, at *a*, an oblong plate, of any suitable material, which may be found to answer the purpose, such plate, in practice, being about twelve inches long.

This plate, in cross-section, is semi-cylindrical or curved, the width of such plate, as well as its curvature, being proportioned or adjusted to a person's mouth.

The upper end of this plate is pushed under the

moustache or beard closely to its roots, and lying upon the person's face.

Dye may now be applied expeditiously and with little care, as any excess will fall upon the shield or plate *a*, and not trickle through or be rubbed upon the skin, whether of the face or lips, as is now the case.

The plate *a* may have combined with it one or more plates *b*, of greater width, in order to accommodate larger moustaches, this auxiliary plate *b* being connected with the former by means of a slot, *c*, and set-screw *d*, the two being laid one upon the other, the set-screw and slot allowing either plate to project, as may be desired.

The number of plates may be increased, but two will undoubtedly be found sufficient, if not superfluous.

I would remark that it may be found, in practice, desirable to serrate the upper end of each plate, in order to facilitate its entrance between the skin and hair, and to form a more perfect protection to the skin of the face and lips.

By means of my invention, the operation of dyeing the moustache may be effected in much less time than at present, since the protection it affords to the skin enables the workman to apply the dye very expeditiously, without danger to the lip or other parts of the face, thus doing away with the greatest obstacle now in the way of coloring hair artificially.

In addition to saving of time, the cleanliness of my invention, as well as the immunity it affords the skin against contact with, and discoloration by the coloring fluid, will recommend themselves to all intelligent people, and to all who artificially color their hair.

What I claim, and desire to secure by Letters Patent, is—

A lip-protector, composed of two or more adjustable curved shields, of different sizes, united and connected in the manner and by the means substantially as herein shown and described.
